(57) **CLAIM**

The ornamental design for a pet toy thrower, as shown and described.

DESCRIPTION

FIG. 1 is a front perspective view of a pet toy thrower, showing my new design, illustrated in a throwing configuration.

FIG. 2 is a rear perspective view of the pet toy thrower of FIG. 1, illustrated in a throwing configuration.

FIG. 3 is a front elevational view of the pet toy thrower of FIG. 1, illustrated in a throwing configuration.

FIG. 4 is a rear elevational view of the pet toy thrower of FIG. 1, illustrated in a throwing configuration.

FIG. 5 is a left elevational view of the pet toy thrower of FIG. 1, illustrated in a throwing configuration.

FIG. 6 is a right elevational view of the pet toy thrower of FIG. 1, illustrated in a throwing configuration.

FIG. 7 is a top elevational view of the pet toy thrower of FIG. 1, illustrated in a throwing configuration.

FIG. 8 is a bottom elevational view of the pet toy thrower of FIG. 1, illustrated in a throwing configuration.

FIG. 9 is a perspective view of the pet toy thrower of FIG. 1, illustrated in an extended configuration.

FIG. 10 is a perspective view of the pet toy thrower of FIG. 1, illustrated in a collapsed configuration.

FIG. 11 is a front elevational view of the pet toy thrower of FIG. 1, illustrated in a collapsed configuration.

FIG. 12 is a rear elevational view of the pet toy thrower of FIG. 1, illustrated in a collapsed configuration.

FIG. 13 is a left elevational view of the pet toy thrower of FIG. 1, illustrated in a collapsed configuration.

FIG. 14 is a right elevational view of the pet toy thrower of FIG. 1, illustrated in a collapsed configuration.

FIG. 15 is a top elevational view of the pet toy thrower of FIG. 1, illustrated in a collapsed configuration; and,

FIG. 16 is a bottom elevational view of the pet toy thrower of FIG. 1, illustrated in a collapsed configuration.

The portions of the drawings that are shown in dashed lines are environmental elements and are not part of the claimed design.
